(57) **CLAIM**

The ornamental design for a swim bra as shown and described.

DESCRIPTION

FIG. 1 is a front perspective view of a swim bra with movable straps in a first arrangement in accordance with a first embodiment of the new design.

FIG. 2 is a front view thereof.

FIG. 3 is a back view thereof.

FIG. 4 is a first side view thereof.

FIG. 5 is a second side view thereof.

FIG. 6 is a top view thereof.

FIG. 7 is a bottom view thereof.

FIG. 8 is a back perspective view thereof.

FIG. 9 is a front perspective view of the swim bra with the movable straps in a second arrangement.

FIG. 10 is a front view thereof.

FIG. 11 is a back view thereof.

FIG. 12 is a first side view thereof.

FIG. 13 is a second side view thereof.

FIG. 14 is a top view thereof.

FIG. 15 is a bottom view thereof.

FIG. 16 is a back perspective view thereof.

FIG. 17 is a front perspective view of a swim bra with movable straps in a first arrangement in accordance with a second embodiment of the new design.

FIG. 18 is a front view thereof.

FIG. 19 is a back view thereof.

FIG. 20 is a first side view thereof.

FIG. 21 is a second side view thereof.

FIG. 22 is a top view thereof.

FIG. 23 is a bottom view thereof.

FIG. 24 is a back perspective view thereof.

FIG. 25 is a front perspective view of a swim bra with the movable straps in a second arrangement.

FIG. 26 is a front view thereof.

FIG. 27 is a back view thereof.

FIG. 28 is a first side view thereof.

FIG. 29 is a second side view thereof.

FIG. 30 is a top view thereof.

FIG. 31 is a bottom view thereof; and,

FIG. 32 is a back perspective view thereof.

The details shown in broken lines illustrate features that form no part of the claimed design.

1 Claim, 24 Drawing Sheets
